UNITED STATES PATENT OFFICE.

MOSES F. CARR, OF LEXINGTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed January 22, 1924. Serial No. 687,750.

This invention pertains to separable fasteners.

It is among the objects of the invention to provide a simple and efficient fastener having a socket of simple and inexpensive construction.

Referring to the drawings, which show two illustrative embodiments of my invention:

10 Figure 1 is a section, partly in elevation, showing a preferred form of fastener;

Fig. 2 is a rear elevation of the socket;

Fig. 3 is a rear elevation of the socket-attaching member, including a clench plate 15 and cap;

Fig. 4 is an elevation of the clench plate;

Fig. 5 is a side elevation of the clench plate;

Fig. 6 is a plan view of the socket;

20 Fig. 7 is a side elevation of the socket shown in Fig. 6;

Fig. 8 is a sectional view of a modified socket; and

Fig. 9 is a side elevation of the modified 25 socket.

In that preferred form of my invention selected for illustrative purposes and shown in Figs. 1 through 7, I have shown a socket casing 11 attached to a curtain 13.

30 The casing 11 is preferably formed from a single sheet of metal presenting an aperture 15 through which a stud 17 passes to engage a spring 19 held within the socket 11. The aperture 15 is only slightly larger than the major diameter of the head of the stud, and the inner face of the aperture lies so close to the neck of the stud as to permit but slight strain on the spring 19 when the stud and socket are subject to lateral strain 35 in opposite directions.

To attach the casing to the curtain 13, I have provided the casing with a rear face formed by a series of petals 23, which, through a portion of their length, fit closely together to form the dome 21. These petals 23 also extend outwardly from the dome to provide attaching prongs which pass through the curtain 13 and are forced into engagement with an attaching member 40

which includes a cap 25, enclosing an anvil 27, against which the prongs are clenched outwardly and downwardly into engagement with a dish-shaped clench plate 29. The anvil 27, clench plate 29 and cap 25 are held, 45 as is usual, in assembled relation by the in-

wardly flanged edge of the cap 25. The clench plate 29 presents a plurality of fabric-engaging spurs 31, which contribute greatly to the firm grip on the curtain between the front plate 25 and the casing 11. 60 The spurs 31 are struck out of the clench plate 29 adjacent the periphery thereof, but the periphery of the clench plate is left intact so as to provide a continuous support for the rolled over edge of the cap 25. The 65 dome 21, because of its shape, prevents collapse of the rear wall of the casing, while the latter is being pressed toward the attaching member and thus secured to the curtain. The walls of the casing are thus 70 held in their normal position and insured against any such collapse of the rear wall of the socket as might interfere with free movement of the spring within the casing 11 when the stud is entered into or withdrawn 75 from the aperture 15.

The modified form of my invention, shown in Figs. 8 and 9, is provided with a casing 33 constructed substantially like that shown in Figs. 1 through 7, except that the 80 prongs 35 are adapted to pierce the fabric, instead of passing through a hole therein, and to prevent cutting of the fabric only alternate attaching prongs are provided, as is best shown in Fig. 9. 85

The attaching member is preferably of the type shown in Fig. 8, wherein the cap or front plate and the anvil 41 are integral, the clench plate preferably being identical with that illustrated in Figs. 1, 4 and 5. 90

While I have shown and described preferred embodiments of my invention, it will be understood that I have done so for purposes of clarification, and not for purposes of limitation. The scope of my invention 95 is best defined by the following claims.

I claim:

1. A fastener socket comprising a casing formed from a single piece of metal to present a continuous peripheral wall, a front 100 face having a stud-receiving aperture therethrough, a back face of substantial area formed by a plurality of inwardly folded petals, petal extensions projecting beyond said back face to provide prongs for engagement with a cooperating clench plate when said socket is secured to a flexible fabric. 105

2. A fastener socket comprising a spring-containing casing presenting a peripheral wall, a front face and a back face, said back 110

face including a dome formed by a plurality of inwardly folded petals, petal extensions extending from said dome to provide prongs for engagement with a socket-securing clenched plate.

3. A fastener socket comprising a spring-containing casing presenting a peripheral wall, a front face and a back face, said back face including a non-collapsing dome formed by a plurality of laterally abutting inwardly folded petals, petal extensions extending from said dome to provide prongs for engagement with a socket-securing clenched plate.

4. A fastener socket comprising a casing formed from a single piece of metal to present a continuous peripheral wall, a front face having a stud-receiving aperture therethrough, a back face of substantial area formed by a plurality of inwardly folded petals, some of said petals projecting beyond said back face to provide prongs for engagement with a cooperating clenched plate when said socket is secured to a flexible fabric.

5. A fastener socket comprising a casing presenting a back face, a plurality of prongs projecting from said back face, a socket-securing cap having an anvil for turning said prongs and a clenched plate for engagement by said prongs, said clenched plate presenting a plurality of spurs struck therefrom for gripping a curtain between said back face and said cap when said prongs are clenched into engagement with said cap.

6. A separable fastener socket having a casing presenting a continuous peripheral wall, a back face integral therewith, a plurality of radially extending and abutting

petals providing a dome having its base spaced from said peripheral wall of the socket, and a plurality of petal extensions providing prongs integral with said petals and projecting from said dome, and an attaching part for location on the opposite side of the socket-carrying fabric from said socket, said attaching part adapted to clenched said prongs for securing said socket to the fabric and presenting a plurality of spurs for gripping the fabric between said casing and said cap at points lying between the peripheral wall of the socket and the base of said dome.

7. A fastener socket attaching member comprising a cover, and a clenched plate, the peripheral edges of said cover having an inwardly extending flange to hold and conceal said clenched plate, said clenched plate centrally apertured to receive attaching prongs on the fastener socket and presenting a plurality of spurs for gripping the socket-carrying fabric, said spurs located adjacent the inner edge of said flange.

8. A fastener socket attaching member comprising a cover, and a clenched plate, the peripheral edges of said cover having an inwardly extending flange to hold and conceal said clenched plate, said clenched plate centrally apertured to receive attaching prongs on the fastener socket and presenting a plurality of spurs for gripping the socket-carrying fabric, said spurs located adjacent the inner edge of said flange and struck from portions of said clenched plate which are concealed beneath said flange.

In testimony whereof, I have signed my name to this specification.

MOSES F. CARR.
